UNITED STATES PATENT OFFICE

168,744

SHOE OR SIMILAR ARTICLE

Preston E. Hiestand, Princeton, Wis., assignor to
The Handcraft Company, Inc., Princeton, Wis.,
a corporation of Wisconsin

Application May 6, 1952, Serial No. 19,613

Term of patent 14 years

(Cl. D7--7)

To all whom it may concern:

Be it known that I, Preston E. Hiestand, a citizen of the United States, residing at Princeton, Green Lake County, State of Wisconsin, have invented a new, original, and ornamental Design for a Shoe or Similar Article, of which the following is a specification, reference being had to the accompanying drawing, forming a part hereof, and wherein:

Fig. 1 is a perspective view of a shoe or similar article showing my new design;

Fig. 2 is a front elevational view thereof; and
Fig. 3 is a plan view of the same.

My design for a shoe of the type shown is characterized by the substantially wide margin between the sides of the shoe upper and the side edges of the sole, and by the stitching at the margin being in substantially the same plane as the top of the sole.

I claim:

The ornamental design for a shoe or similar article, as shown and described.

PRESTON E. Hiestand.
